UNITED STATES PATENT OFFICE.

JACOB E. BUERK, OF BOSTON, MASSACHUSETTS, ASSIGNEE OF JOHN BÜRK.

IMPROVEMENT IN WATCHMAN'S TIME-DETECTORS.

Specification forming part of Letters Patent No. 31,052, dated January 1, 1861; Reissue No. 2,054, dated August 22, 1865.

To all whom it may concern:

Be it known that J. BÜRK, of Schwenningen in the Kingdom of Würtemberg, Germany, invented a new and Improved Watchman's Control, which invention was assigned to me, JACOB E. BUERK, of Boston, in the county of Suffolk and State of Massachusetts; and I do hereby declare that the following is a full, clear, and exact description of the same, reference being had to the accompanying drawings, forming part of this specification, in which—

Figure 1 represents a face view of this invention when closed and ready for operation. Fig. 2 is a plan or face view of the same, the cover having been removed to expose the working parts. Fig. 3 is a side elevation of this invention, the case having been cut open to expose the working parts. Fig. 4 is a vertical central section of the same. Fig. 5 is an elevation of the several keys which are used for operating my watchman's control. Fig. 6 is an elevation of the key used for setting the same and to wind it up. Fig. 7 is a plan or face view of the strip of paper which gives an account of the circuit of the watchman.

Similar letters of reference indicate corresponding parts in the several figures.

All devices heretofore used for the purpose of controlling watchmen are of a complicated construction which renders the same very expensive and in many cases very liable to get out of order and difficult to repair. Furthermore, most of these devices can only be used in one spot, and in each room, and other place in the circuit or beat of the watchman, a separate controlling device has to be provided.

A watch which the watchman can carry with him, and which gives a clear, true, and permanent picture of the circuit of the watchman in regard to time and direction, is of a decided advantage, and if this object can be obtained by a device which is at once very simple and not subject to the disadvantage of a complicated mechanism, and can be got up with little expense, and for this very reason brought into common use, a watchman's control is obtained which is far superior to anything now in use; as far as convenience, security, and simplicity are concerned, and which offers a considerable advantage as regard the security of the public.

This device is so arranged that it can be combined with every stout watch, or with any other portable clock-movement, and it is inclosed in a strong metallic case. It is placed in the hands of the watchman, locked just before he starts on his beat, and on his return he gives it back to the superintendent or supervising officer, who, on opening the same can find the precise time when the watchman has visited the several stations to be visited on his beat, which direction he has taken, in which order he has visited the several stations, what delays and deviations have occurred, how long he has tarried on the way between the several stations and on the stations themselves, &c. This purpose is effected by a movable strip made of paper or other suitable material, and marked off into a convenient number of parts to represent hours of the day, in combination with a chronometer, and with one or more points or devices for piercing said movable dial in such a manner that, by the indentations produced in the movable strip, the time when the watchman has visited the station or stations is recorded, and can be ascertained at any time after the watchman has completed his round. If only one station is to be visited by the watchman, either the chronometer-movement or the device for piercing the movable strip may be stationary, but when more than one station is included in the beat of a watchman different keys, or other devices used for producing the indentations in the movable strip, are firmly secured, one at each station, and the watchman carries the chronometer from one station to the other, and by inserting the key or other device in each station produces the indentations which form a record of the time when he has passed such station or stations.

To enable others skilled in the art to make and use this invention, I will proceed to describe its construction and operation with reference to the drawings.

The drum A, which is provided on its edges with small projecting flanges, is fitted on the arbor of the hands of a watch or clock movement, the minute-hand having been taken off, and a slot in the lower edge of its hub a fits over the hour hand in such a manner that said drum is caused to rotate once in twelve hours with the hour-hand. It is retained in

its place by a bar, *b*, which is hinged to a post, *c*, on one side of the dial, and which is secured by a spring-catch, *d*, on the opposite side, and a pin, *e*, which projects from the lower surface of said bar into a central opening in the hub of the drum, serves to keep the same steady during its motion. Beyond the drum, and secured to the face-plate of the watch, which is somewhat larger than said drum, are a series of spring-points, *B*, one above the other. Said points are turned toward the circumference of the drum, and they stand exactly opposite the figure XII on the dial of the watch. Close behind these spring-points, and firmly fastened in the face-plate, is a pin, *f*, that receives the several keys *C*, which serve to operate the springs. The whole is covered up by the cover *D* of the case *E*, and a small lock, which is attached to the inner side of the case, serves to fasten said cover.

If a strip of paper or other suitable material is now wound around the drum *A*, and if one or more of the points are forced up against the circumference of said drum by one or more of the keys, *C*, which are inserted on the pin *f* through a suitable key-hole, *c*, in the cover *D*, small holes are produced in said movable strip by the action of the pins. The circumference of the drum is provided with grooves corresponding in number to the spring-points, and just opposite to the same, so that the space below those portions of the paper which are to be penetrated by the points is hollow, and that the points pass through the paper without becoming injured. The strip of paper *F* is divided in twelve hours, and into the required parts of hours by lithographic printing, and it is retained by a small point projecting from the face of the drum. The division on the strip goes from six to six, or it may commence or end with any other hour, as may be desirable. In placing the strips on the drum the dot in the figure 6 on the black end of the paper is pressed on the point of the drum, and the strip of paper is drawn from left to right, thereby bringing the dot in the figure 6 at the white end of the paper also on the point of the drum. The number of the holes produced in the paper depends entirely upon the form of the bit of the key, for if this bit is so arranged that the same depresses 1, 2, 3, 4, &c., spring-points an equal number of holes are produced on the corresponding places of the paper. The strips of paper are colored red at their under sides, and are provided with gum or mucilage for the purpose of fastening them into a book, and as they are made moist for this purpose the red color penetrates through the holes, and makes them appear perfectly clear and distinct on the upper surface of said strips.

The operation of this device will be easily understood. In the beat of the watchman a number of stations are selected which are to be visited regularly by the watchman at every hour or at certain fixed intervals. In each of

these stations a small closet is secured, and in the closet, secured by a chain, or by any other desirable means, is one of the controlling-keys *C*; said chain is attached in the interior of the closet in such a manner that the key cannot be taken away.

The watch is wound up every day by the superintendent, and a fresh strip is fastened to it. After the strip has been replaced, the watch is locked. The key remains in the hands of the superintendent. In this state the watchman receives the watch, and all he has to do is, on reaching the several stations, to take the keys fastened in the same, insert them into the key-hole in the cover of the case, and turn them so as to force the spring-points through the paper at the respective spots.

The number of the holes produced by the spring-points can be made to correspond to the number of the stations; on the first station one hole, on the second two, on the third three, and so on if the number of the stations does not exceed that of the points. If the number of the stations exceeds that of the points, they can be marked on the strip of paper by various combinations of the points without changing in the least the construction of the apparatus. Six spring-points will be sufficient for a large number of stations, notwithstanding the fact that it is not necessary to designate a great many stations, since a small number of stations can be selected so as to compel the watchman to pass over the entire beat in going from one station to the other. It is still of no small advantage to be able to use the same watch for a large number of stations, since its use is not restricted to single houses, manufacturers, or towns, but it may be used with advantage on post-routes and railroads.

At the end of the day the watch is returned to the superintendent; he opens it, takes out the movable strip, replaces it by a new one, winds up the watch, sets it if necessary, locks it, and returns it to the next watchman. On the movable strip he finds everything marked as herein above stated, and if it is desired to know how long the watchman has tarried on each station it is only necessary to order him to turn the respective keys at the moment he reaches each station, and again just before he leaves the same.

For the purpose of setting the watch, the same key is used which serves to wind it up. This key is represented in Fig. 6 of the drawings, and it will be noticed that it has a pin, *g*, inserted in its side; this pin represents the minute-hand of the watch, and the key is inserted in the central arbor of the watch, so that said arbor corresponds with the position of the minute-hand, and it is now turned until it corresponds with the proper figure to designate the correct time.

The principal advantage of this device is that it can be carried conveniently in the pocket, its construction is exceedingly simple and durable, and it can be made and sold at a reasonable cost. It is so arranged that the

same watch can be used for any number of stations without changing its construction, or rendering it more complicated; it can be placed into the hands of the most awkward watchman, since it makes no difference in what direction or how often the keys are turned; it is easy to prevent an imitation or forging of the keys by the watchman simply by changing the keys sometimes without the knowledge of the watchman. It gives the means to read off the correct account of each station by taking out the movable dial, and it enables the superintendent to keep a continuous account of the manner in which the watchman performs his duty by pasting the several strips of paper on the leaves of a book which is kept for this purpose.

Having thus fully described this invention, what is claimed as new, and desired to be secured by Letters Patent, is—

1. The use of a movable strip made of paper or other suitable material, and marked off in a convenient number of parts, in combination with a chronometer-movement, and with one or more points or devices for producing marks or indentations on said movable strip, substantially as and for the purpose set forth.

2. The employment of a series of keys, C, with bits of different shape, in combination with spring-points B, and with a drum, A, carrying a strip of paper, F, and rotated by a clock-movement, substantially as and for the purpose specified.

The above specification of my reissue signed by me this 10th day of June, 1865.

J. E. BUERK.
